CONVERSION OF HYDROCARBONS

Richmond T. Bell, Highland Park, Hillis O. Folkins, Skokie, and Carlisle M. Thacker, Highland Park, Ill., assignors to The Pure Oil Company, Chicago, Ill., a corporation of Ohio

No Drawing. Application February 12, 1944,
Serial No. 522,086

14 Claims. (Cl. 196—52)

This application is a continuation-in-part of application Serial No. 482,608, now Patent No. 2,374,167, and relates to conversion of hydrocarbons to lower boiling hydrocarbons or to the conversion of hydrocarbons into hydrocarbons containing less hydrogen in the molecule.

One of the objects of the invention is to provide an improved method for converting hydrocarbons into lower boiling hydrocarbons.

Another object of the invention is to provide catalysts or sensitizers which can be used in conventional types of cracking processes to accelerate the rate of cracking or to make possible cracking of hydrocarbons at lower temperatures.

Other objects of the invention will become apparent from the following detailed description.

In accordance with our invention, the hydrocarbon to be converted is passed through a reaction zone together with a small amount of an aliphatic organic compound containing a member of the halogen group of elements and a member of the oxygen family. We have found that aliphatic hydrocarbons containing both halogen and oxygen, sulfur, selenium or tellurium substituted in the molecule have a marked effect in accelerating cracking of hydrocarbon oils and gases into lower boiling hydrocarbons and into more unsaturated hydrocarbons. Halogenated derivatives of the following general groups of compounds are effective: alcohols, aldehydes, acids, ethers, ketones, esters and epoxy compounds. Epoxy compounds are those having an oxygen atom bonded to different radicals already united in some other way. The halogen may be substituted for hydrogen in one or more alkyl or other radicals. For purposes of brevity the term oxy-halogenated will hereinafter be used to mean compounds containing halogen and one or more members of the oxygen family, viz., oxygen, sulfur, selenium, tellurium.

As specific examples of compounds which we have found will accelerate the cracking of hydrocarbons are ethylene bromohydrin, ethylene chlorohydrin, chloral, dichloracetylchloride, chloromethyl ether, ethyl chloracetate and the epoxy compounds, epichlorohydrin and epibromohydrin.

In carrying out our invention, the hydrocarbons undergoing reaction should contain in admixture therewith from 0.1 to 5 mole percent of the oxy-halogenated aliphatic compound, although we prefer to use from .25 to 3 mole percent. Higher or lower amounts of sensitizer may be used but within the range above specified the increase in reaction rate is very marked and formation of undesirable amounts of halogen and/or oxygen reaction products is avoided.

Although oxy-halogenated compounds in which chlorine is substituted for any element or radical in the molecule are effective, we have found that bromine-substituted compounds are much more

effective than chlorine substituted compounds. For example, epibromohydrin appears to be approximately ten times as effective as epichlorohydrin when used in amounts of 1 mole percent.

Our invention may be carried out in conventional cracking apparatus either of the straight thermal or catalytic type. The sensitizer may be mixed with the hydrocarbon oil, vapor or gas undergoing conversion prior to charging it to the reaction zone, or the sensitizer may be injected directly into the reaction zone. Although we prefer to use sensitizers which are in the same physical state as the hydrocarbons at reaction temperature, compounds may be used which exist in a different physical state from the hydrocarbons at reaction temperature. The sensitizer, if soluble in the hydrocarbons undergoing conversion, may be dissolved therein prior to passage through the reaction zone, or may be dissolved in a small portion of the hydrocarbons undergoing reaction and fed into the main stream of hydrocarbons in desired proportions. If the sensitizer is insoluble in the hydrocarbon undergoing reaction, a slurry of the sensitizer in a portion of the hydrocarbon oil may be prepared and fed in desirable proportion into the main stream of oil. Where it is desired to crack gases or oil in vapor phase, a sensitizer is preferably selected which vaporizes readily and can be mixed with the vapors undergoing conversion. We prefer to introduce the sensitizer into the mixture undergoing reaction in such manner that decomposition of the sensitizer does not occur until it is in contact with the hydrocarbons undergoing decomposition at reaction temperature. One method of doing this is to flash inject the sensitizer into the reaction chamber without appreciably preheating it.

Cracking with sensitizers in accordance with our invention may be carried out under sub-atmospheric, atmospheric or superatmospheric pressure and at temperatures from the lowest temperatures at which cracking will occur to temperatures of approximately 2000° F., depending upon the type of product it is desired to produce. Where cracking of hydrocarbon oil is conducted for the purpose of making lighter oil, such as gasoline, temperatures ranging from approximately 650° to 1200° F. may be used. Where cracking of hydrocarbon oils or gases for the purpose of making aromatic hydrocarbons is practiced, temperatures of approximately 1000 to 1500° F. may be used. Where it is desired to produce butadiene from hydrocarbon oils, temperatures from the vicinity of 1300 to 1600° F. may be used, and where it is desired to crack hydrocarbon oils to gases, hydrocarbon temperatures of from approximately 1200° to 2000° F. may be used.

In order to demonstrate the invention, a series

of runs was made using normal butane as charging stock. The runs were all made at a temperature of 525° C. in laboratory apparatus constructed of Pyrex glass. Before each run, the reaction vessel was evacuated to 0.001 mm. or less of mercury while maintaining the temperature at the desired reaction level. Normal butane admixed with the desired amount of sensitizer was then charged to the reaction chamber until the pressure therein was approximately atmospheric pressure. Pressure increases in the reaction chamber were noted at definite intervals ranging from 0.5 to 2 minutes until a pressure increase of 25% had been attained. At the time the pressure increase reached 25%, the reaction chamber was quickly evacuated and the reaction products were analyzed for carbon dioxide or acidic constituents by absorption in caustic potash solution, for unsaturates by absorption in fuming sulfuric acid, for hydrogen by contraction in volume due to water formation, and for carbon monoxide by oxidation followed by absorption in caustic potash solution.

In certain runs indicated in the following table, the pressure rose to a point above a 25 percent pressure increase before the run was terminated. In these runs the time required for a 25% pressure increase was interpolated from a curve based on time and pressure observed during the run.

In addition to the runs made with epichlorohydrin and epibromohydrin as sensitizer, a number of blank runs were made in which only normal butane without sensitizer was charged to the reaction vessel.

The following table contains in tabulated form the results observed on the various runs.

sensitizer. The sensitization factor is therefore a true indication of the rate of acceleration of the reaction caused by the sensitizer. In determining sensitization factors the average figures for the blank runs immediately preceding a sensitized run in the table were used as a basis for comparison. As is apparent from the table, although both epichlorohydrin and epibromohydrin sensitized cracking reaction to a marked extent, epibromohydrin is far superior to epichlorohydrin. With 1 mole percent of epibromohydrin in the reaction mixture the reaction rate was increased almost 2400 percent.

The reaction products formed in the runs regardless of whether sensitizer is present or not present are fairly uniform and as indicated by the large amount of unsaturates formed and the low amount of hydrogen, the reaction is primarily one of splitting of the carbon to carbon bond. The larger amount of unsaturates formed in runs 1034-F. and 1035-F. is due to the fact that these runs were carried to a point in excess of 25 percent pressure increase.

Our invention is applicable to improvement of various types of thermal cracking operations now in commercial use in which no catalyst is used and also to improvement of catalytic cracking processes of known commercial types. It is possible to improve present commercial cracking operations without the necessity of changing the process and apparatus except to make provision for charging a small amount of sensitizer to the operation.

In the claims the group

Table

¹ Run carried to 34.8% pressure increase.

² Run carried to 26.7% pressure increase.

The sensitization factor for pressure changes of 5%, 12.5% and 25% pressure increase is obtained by dividing the time required for the particular pressure increase without sensitizer by the time required for the same pressure increase with

is the radical resulting from the removal of one hydrogen atom from epoxyethane.

We claim:

1. The method of cracking hydrocarbons which comprises subjecting said hydrocarbons to suit-

able cracking conditions of time, temperature and pressure in the presence of a small amount of a halogenated epoxy compound.

2. Method according to claim 1 in which the halogenated epoxy compound contains the group

in the molecule.

3. Method in accordance with claim 1 in which the halogenated epoxy compound is epibromohydrin.

4. Method in accordance with claim 1 in which the halogenated epoxy compound is epichlorohydrin.

5. The method of cracking hydrocarbons which comprises subjecting said hydrocarbons to temperatures of 650 to 2000° F. in the presence of from approximately 0.1 to 3 mole percent of a halogenated epoxy compound.

6. Method in accordance with claim 5 in which the epoxy compound contains the group

in the molecule.

7. Method in accordance with claim 5 in which the halogenated epoxy compound is epibromohydrin.

8. Method in accordance with claim 5 in which the halogenated epoxy compound is epichlorohydrin.

9. Method of cracking hydrocarbons containing at least three carbon atoms per molecule which consists in subjecting said hydrocarbons

10

to temperatures between 650° and 2000° F. in the presence of about 0.1 to 3 mole percent of epibromohydrin.

10. The method of cracking propane-containing gas for the production of ethylene which comprises subjecting said gas to cracking temperatures in the presence of a small amount of a halogenated epoxy compound containing the group

11. Method in accordance with claim 10 in which the halogenated epoxy compound is epibromohydrin and it is present in amounts from 0.1 to 3 mole percent.

12. The method of cracking hydrocarbon oil comprising contacting said oil with a small amount of epibromohydrin at temperatures of 650 to 1200° F. for sufficient time to obtain a substantial yield of hydrocarbons of gasoline boiling range.

13. Method in accordance with claim 12 in which the epibromohydrin is present in amounts of approximately 0.1 to 3.0 mole percent of the hydrocarbon oil.

14. Method in accordance with claim 9 in which the hydrocarbon is butane, the temperature is approximately 977° F. and the epibromohydrin is present in an amount of 1 mole percent.
